UNITED STATES PATENT OFFICE.

FREDERICK J. YANDLE, OF SANTA ROSA, CALIFORNIA.

PRUNE GRADER, CLEANER, AND SPREADER.

1,162,123.

Specification of Letters Patent. Patented Nov. 30, 1915.

Application filed June 2, 1914. Serial No. 842,380.

To all whom it may concern:

Be it known that I, FREDERICK J. YANDLE, a citizen of the United States, residing at Santa Rosa, in the county of Sonoma and State of California, have invented new and useful Improvements in Prune Graders, Cleaners, and Spreaders, of which the following is a specification.

This invention relates to a prune grader, cleaner and spreader.

One of the objects of the present invention is to provide a machine of the character described, which is simple and substantial in construction and which requires comparatively small power for its operation, and which is particularly capable of separating prunes of various sizes and spreading them onto separate trays clean and free from bruises.

Another object of the invention is to provide double or compound grading screens of the shaking type, and of different mesh, for separating the prunes, in combination with an endless belt grading screen; and to provide means for adjusting the throw of the shaking screens.

Further objects will hereinafter appear.

The invention consists of the parts and the construction and combination of parts as hereinafter more fully described and claimed, having reference to the accompanying drawings, in which—

Figure 1 is a side elevation of the machine. Fig. 2 is a plan view of same. Fig. 3 is a cross section through the spreader platform.

Referring to the drawings, A indicates the main frame of the machine, preferably made of wood, in the form shown in Figs. 1 and 2. The frame is provided with a top rail 2 to which is attached the main operating parts of the machine.

3 and 4 are grading frames provided with bottoms formed of perforated plates or screens 5. The holes therein, through which the fruit passes, are of varied diameters, decreasing in size from the higher to the lower screen. The upper grading frame 3 is suspended by links 6 and 7 from the upper rail 2 and the lower grading frame 4 is in turn suspended by links 8 and 9 from the upper grading frame. Mounted below the grading frames is an endless traveling screen belt

10 by which the smallest grade of prunes is removed and through which any foreign material, such as stems, leaves and sand, is permitted to escape. The endless traveling screen belt is secured to a pair of sprocket chains 11 and 12, which in turn are mounted on sprocket wheels 13 and 14 secured on shafts 15 and 16 respectively, journaled in boxes 17 and 18 carried by the lower rail 2 of the frame. Power to drive the belt is transmitted from any suitable source through a pulley 19 secured upon the shaft 16.

Shaking movement is transmitted to the upper and lower grading frames through the following mechanism: Suitably secured, as at 20, on the lower side of the upper rail 2 is a box 21, in which is pivotally mounted a rocker-arm 22. The lower end of the arm is pivotally connected, as at 23, to the grading frame 4, and the other side of the arm, above the pivot point, is pivotally connected, as at 24, to the upper grading frame. The extreme upper end of the arm is provided with a series of perforations 25 in any one of which may be secured one end of a link 26, the other end of said link being secured, as at 27, to the upper end of a double crank-arm 28 which is pivotally mounted in a box 29 mounted on the upper rail. The lower end of the crank-arm 28 is connected by a link 30 with an eccentric 31, or like means, which is secured upon a shaft 32 carried by a box 33. The box 33 is secured on the lower side of the top rail and power to drive the shaft 32 is transmitted through a pulley 34, secured on shaft 16, to a pulley 35 secured on the eccentric shaft by means of a belt 36.

The adjustable connection formed on the extreme upper end of arm 22 permits the throw or shaking movement of the grading frames to be adjusted to suit various conditions, and the peculiar suspension of the grading frames secured by the links 6, 7, 8 and 9, together with the connections 23 and 24, will, with the main rocker-arm 22 transmit opposite movements to the screens and at the same time impart a slight sidewise movement to same which has a peculiar effect as far as the grading of the fruit is concerned.

The prunes to be graded are deposited upon the upper grading frame through

means of a hopper or chute indicated at 37. The screen bottom formed in the upper grading frame is provided with large openings, as indicated at 38. The smaller prunes will thus pass through said screen while the larger size prunes will be retained. The angle of the grading frames will, however, cause the prunes to travel down toward the discharge end of the frame where they are thoroughly spread and permitted to escape, as at 39. The next size prunes are caught on the lower grading frame, indicated at 4, and are similarly discharged, as at 40, on the opposite side of the machine, while the smallest grade of prunes are permitted to pass through to be finally deposited on the endless traveling screen belt 10 by which they are conveyed to the front of the machine and finally discharged, as at 41. All foreign matter, such as stems, leaves and sand, will fall through the endless traveling screen belt and may be collected in a catch pan or like device (not here shown) placed under the belt where they may be gathered and conveyed away from the machine in any suitable manner.

The shaking movement transmitted to the grading screens, by means of the connections 23 and 24, with the arm 22 which is positioned approximately centrally between the links 6, 7, 8 and 9 has a tendency to impart a slight side movement at the same time that an end to end movement in opposite directions is imparted. This slight movement is permitted by the loose connections in the suspending links and is very effective, as it not only causes the fruit to roll over from end to end, but it also imparts a slight turning movement to same. The position of the fruit is thus constantly changed while passing over the screen surface of the grading frames and is thus given ample opportunity to escape on the right screen. The fruit is furthermore prevented from being bruised, as the shaking movement imparted in the manner shown does not necessarily have to be as violent as in other types of machines.

A machine constructed as here shown does not only grade the fruit into three sizes, but it also acts as a cleaner and spreader. If it is desired to dry the fruit directly after the grading action has taken place, it is only necessary to place the drying trays directly under the discharge points 39, 40 and 41. These points are widely separated and ample space is thus provided for the handling of the trays or like means by which the fruit is carried away from the machine. The machine is simple in construction and may be easily adjusted to suit various conditions and grades of fruit. It, furthermore, consumes very little power and is so simple in construction that it may be successfully operated by anyone.

65 Various changes in form, proportions and

minor details of construction may be resorted to within the scope of the appended claims and I do not wish to limit myself to the specific design and construction here shown.

An extension platform 45 is provided on each side of the main frame upon which the trays to receive the prunes may be placed. These platforms are pivotally secured at their outer ends, as at 46, while the inner 75 ends are supported by coil springs 47. Each platform will normally assume an angular position, as shown in Fig. 3, when an empty tray is placed thereon, but they will gradually assume a horizontal position as 80 they become loaded or filled with prunes; that is, the tension of the springs 47 is such that they will gradually yield and allow the trays to assume a more and more horizontal position as they become filled, whereby a more complete and even filling is assured. This action may be facilitated by so mounting the platforms as to permit them to be shaken so that the prunes, as they deposit on the trays, will be evenly spread thereon, 85 and this shaking movement is transmitted to each platform and the tray mounted thereon in the following manner: Suitably secured to one end of each tray, as at 48, is a universal joint and connecting said pivot 95 with either the upper or lower grading frame, as at 49, is a link 50. The shaking movement of the grading frames is thus transmitted to each individual tray supporting platform and the prunes discharging 100 from the individual grading frames are thus evenly spread over the trays.

Having thus described my invention, what I claim and desire to secure by Letters Patent is—

1. In combination with superposed screens and means to shake same, means beneath the lowermost screen to receive material and to discharge same at the fronts of the screens, a pair of separate and independent lateral 110 oppositely disposed discharges for the respective screen fronts connected to the respective screens and movable therewith, and a pair of receivers beneath the respective discharges and on opposite sides of the receiving means at the discharge end of the latter.

2. In combination with superposed screens having separate front lateral discharges connected to the respective screens and movable therewith, an endless conveyer beneath and adapted to receive material from the lowermost screen and arranged to discharge the material at the front of the conveyer, and between said lateral discharges.

3. In a spreader, a receiver, means to pivotally support the receiver at one end, a spring underlying the opposite end of the receiver to resiliently support the latter and to allow said end of the receiver to move 130

downwardly under the weight of material that enters the receiver, and means connected to the last named end of the receiver to shake said receiver.

4. In a spreader, a receiver, means to pivotally support the receiver at one end, spring means to resiliently support the opposite end of the receiver, and means to impart movement to the receiver so as to cause the same

to be reciprocated about said pivot and **10** against the action of the spring means.

In testimony whereof I have hereunto set my hand in the presence of two subscribing witnesses.

FREDERICK J. YANDLE.
